UNITED STATES PATENT OFFICE

CARL F. GOUDY, OF FLUSHING, NEW YORK, ASSIGNOR TO PACENT ELECTRIC CO., INC.,
OF NEW YORK, N. Y., A CORPORATION OF NEW YORK

DESIGN FOR AN ELECTRIC PHONOGRAPH PICK-UP OR SIMILAR ARTICLE

Application filed June 14, 1929. Serial No. 31,685. Term of patent 14 years.

To all whom it may concern:

Be it known that I, CARL F. GOUDY, a citizen of the United States, residing at Flushing, county of Queens, and State of New York, have invented a new, original, and ornamental Design for Electric Phonograph Pick-ups or Similar Articles, of which the following is a specification, reference being had to the accompanying drawing, forming part thereof.

Figure 1 is a perspective view of the article showing my new design for electric phonograph pickups.

Figure 2 is an end view of the device.

I claim:

The ornamental design for an electric phonograph pickup, or similar article, substantially as shown.

CARL F. GOUDY.
